UNITED STATES PATENT OFFICE.

JOSEPH NIEBLING, OF WOODCLIFF LAKE, NEW JERSEY.

FASTENER FOR FILE-BINDERS.

1,268,757

Specification of Letters Patent. Patented June 4, 1918.

Application filed April 26, 1917. Serial No. 164,691.

To all whom it may concern:

Be it known that I, JOSEPH NIEBLING, a citizen of the United States, and a resident of Woodcliff Lake, in the county of Bergen and State of New Jersey, have invented certain new and useful Improvements in Fasteners for File-Binders, of which the following is a specification.

This invention relates, generally, to that class of binders wherein the papers to be filed, whether printed, typewritten, manuscript, or plain blank sheets, are placed between two covers united by an expansible backing, and are maintained in position therein by hinged strips, respectively attached to the opposite covers and secured to the corresponding sides of the papers at the inner edges. In a more restricted sense, the invention has reference to the means employed for fastening the papers intermediately of the hinged strips.

The main object of the invention is the provision of means enabling a fastener of the class mentioned to be used in reverse or changed positions, so that it can accommodate itself to paper sheets of different lengths, thereby rendering the binder available for filing papers, of diverse sorts, the sizes of which may vary to a desirable extent, longitudinally and transversely, within the binder's dimensions.

Other objects and advantages will become apparent as the specification proceeds.

With the aforesaid objects in view, the invention consists of the improvements, novel construction, arrangements and combinations of parts hereinafter described, defined in the subjoined claims and illustrated in their preferred embodiments by the annexed drawings, wherein like elements are designated by the same reference characters throughout the different views.

In the said drawings:—

Figure I is a broken plan view of a binder provided with a pair of fasteners made in accordance with the invention, the upper fastener being shown as partly applied, while the lower fastener appears as already fixed in position;

Fig. II is a front edge view of the same, excepting the lower part of the binder, which is sectioned along the line 2—2 of Fig. I, looking rearward as pointed out by the arrows pertaining to this section line;

Fig. III is a transverse section on the line

3—3 of Fig. I, looking up in the direction indicated by the middle arrows; and

Fig. IV is a fragmentary bottom plan view, showing the underside of the fastener.

The binder proper is of book form, including two covers A and B, joined with each other at one edge by means of a flexible backing C, which permits the said covers to be spaced apart to a greater or less extent in proportion to the size of the file of papers, as P, placed between the same. A pair of flaps or strips D and E is also attached, at or near the said edge, to both the covers and their said backing, the connection therewith being made flexible so that the said flaps or strips will operate as a pair of hinges adapted respectively to lap over the opposite sides of the papers, at their inner margins thereof, when they are inserted in the binder or file. These parts are of known construction and not claimed herein, save in so far as they enter into legitimate combination with the several coacting elements of the improved fastener disclosed in the present application.

Overlying the top hinge strip D, is a plate 11, which by preference is made to extend transversely for the full width thereof, and is of sufficient length to assist in providing suitable bearing surfaces for parts of a certain binding element herein-after described. This plate is conveniently secured to the strip D, by means of eyelets as 12, 13.

A hook-shaped member 16 is formed integral with the said plate 11, the free end and sides of this member being cut out and bent up from the middle portion of the plate. Preferably and as shown, the said free end is brought to a point 17, which is turned up also relatively to the member and directed toward the rear edge of the plate, crosswise of the strip D. The fixed end of the member is somewhat broader and remains connected to the plate on a line parallel with the outer edge of the hinge-strip to which it is anchored.

To the other hinge strip E, and preferably on the under side thereof, is attached a flexible impaler 21, designed to pass through registering perforations in the file papers, and constituting the binding element therefor previously mentioned. As shown in Figs. II and IV, the binding impaler 21 has an annular base 22, adapted to receive an

eyelet 23, and to be held thereby to the strip E. The connection is loose between the base and the eyelet, so that the impaler is pivotally attached to the latter named strip and may be turned thereunder toward either end of the file. According also to the preferred mode of construction, the pivotal attachment of the impaler to the strip is effected at a point in substantial alinement 10 with the central opening left in the plate 11 by cutting out therefrom the before described hook-shaped member 16.

Normally, it is intended that the binding impaler 21 should run first outwardly endwise of the file, from the pivot eyelet 23 to an aperture 24, in the hinge-strip E, which aperture is located directly opposite the before mentioned eyelet 12, that serves to anchor the outer end of the plate 11, upon 20 the hinge-strip D. The aperture 24 and eyelet 12 constitute alined bearings, through which the free portions of the impaler can be successively passed and bent upward and inward, as illustrated in the lower half of 25 Fig. II, and the corresponding half of Fig. I. It will be noted that such portion of the impaler as runs between these alined bearings is thereby held straight and maintained in that condition while passing through the 30 interposed papers. From the eyelet 12 the impaler is made to run inwardly along the plate 11, and caused to engage the hook-shaped member 16, the function of which is to act as a retainer for the free end of the 35 impaler, as will be understood. Thence the binding impaler may extend above the other anchoring eyelet 13, to and beyond the inner end of the plate 11, its length depending upon the number of papers, sheets or thickness 40 of file for which it is provided.

Being pivotally connected with the hinge-strip E, the aforesaid impaler 21 can be turned at first inwardly endwise of the file, if desired, as indicated by dot-and-dash 45 lines in the upper half of Fig. II. In such a case, the binding impaler is arranged to run from the pivot 23 to another aperture 27, in the hinge-strip E, which latter aperture is situated opposite the inner anchoring 50 eyelet 13 of the plate 11 on the hinge-strip D, and forms therewith a second pair of alined bearings for the free portions of the impaler. Having been passed through this 55 pair of bearings, and the intervening paper sheets, as represented by the dot-and-dash lines in the said upper half of Fig. II, the free end of the impaler will then be turned outwardly endwise of the file, in a direction opposite to that followed for the normal application of the impaler, as before 60 described. The engagement of the free end of the impaler with the retaining hook-shaped member 16 will be similar to that in the other case, though effected also in a reverse direction. From the member 16 the

free end of the impaler may extend above the eyelet 12, and reach the outer extremity of the plate. The advantage in having a pivot and a double pair of alined bearings for the impaler, it will be observed resides 70 in that the latter can be turned and positioned so as to accommodate any one of several different lengths of files with a single binder. Thus, for example, a binder capable of receiving paper sheets of legal or 75 foolscap size may be utilized for filing copies of letters and invoices of similarly reduced dimensions, merely by reversing from normal position either one or both of the impalers pertaining to the binder's fasteners. 80

It will be noted that the binding element or specifically the binding impaler, herein described and illustrated is so applied that it provides confining members of equal lengths on the opposite outer faces of both 85 the hinge-strips whichever way the said element or impaler is turned. These confining members cause an even embrace of the hinge-strips upon the opposite sides of the file papers, at the inner edges which serves to 90 keep the file in a flat and firm condition. To assist in producing this desirable condition the impaler is preferably made of tough and pliable metal, in the form of a long blade or tongue, as exemplified in the 95 drawing hereto annexed. The symmetrically disposed anchors and bearings 12, 13, 24, 27 in the hinge-strips, through which the impaler passes take up all stress that the bends thereof might otherwise exert on the 100 papers placed in the file, and the oppositely located pivot 23 and retainer 16 maintain the set portions of the impaler in equipoise. At the same time, as the free end of the impaler is unattached to the retainer, it forms 105 a supple tie which yields and gradually recedes in proportion as the file becomes expanded, and vice versa it advances in like ratio if the volume of the file be diminished.

While a certain preferred embodiment of 110 this device has been shown and described, it will be understood that changes in the form, arrangements, sizes, proportions and details thereof may be made without departing from the scope of the invention as defined by the appended claims.

Having described my invention what I desire to secure by Letters Patent and claim is:

1. The combination with binding hinge strips having alined apertures, provided in pairs therein, of a retainer on one of said strips secured intermediate of said apertures and a pliable impaler pivotally connected with the other strip so as to enable it 125 to be passed through either one of the paired apertures.

2. The combination with binding hinge strips having paired openings at suitable intervals therethrough, of a pliable impaler 130

pivotedly attached to one of said strips in such a manner as to permit it to traverse either pair of said openings, and a retainer on the other strip adapted to engage the free end of said impaler after it is drawn from either of the openings.

3. The combination with binding hinge strips having a plurality of apertures provided in the same, of an anchor on one of said strips located intermediately of said apertures, a pliable impaler journaled to said anchor in position to enter one of the apertures at either side thereof, and a retainer on the other strip capable of engagement with the free end of said impaler coming in either direction.

4. The combination with binding hinge strips, of a plate partly covering one of said strips exteriorly thereof and formed

with openings in different parts of the same, 20 said openings being capable of registering with similar openings in the other strip, an anchor secured to the latter intermediately of the openings, a retainer occupying a corresponding position on the plate, and a pliable impaler pivotally connected to said anchor so as to permit it to traverse either one of the openings and thence to engage said retainer while reclining over the plate from either end of the latter.

Signed at the borough of Manhattan in the county, city and State of New York this 24th day of April, 1917.

JOSEPH NIEBLING.
